(57) **CLAIM**

We claim the ornamental design for the beam assembly, as shown.

DESCRIPTION

FIG. 1 is a perspective view of a top, front and first end of the beam assembly of the present invention;

FIG. 2 is a front elevational view of the beam assembly;

FIG. 3 is an elevational view of the first end of the beam assembly;

FIG. 4 is a rear elevational view of the beam assembly;

FIG. 5 is an elevational view of a second end of the beam assembly;

FIG. 6 is a top plan view of the beam assembly; and,

FIG. 7 is a bottom plan view of the beam assembly.

Broken lines in the drawings form no part of the design as claimed.
